UNITED STATES PATENT OFFICE.

LOUIS SCHWITZER, OF INDIANAPOLIS, INDIANA, ASSIGNOR TO AUTO MOTIVE PARTS CO., OF INDIANAPOLIS, INDIANA, A CORPORATION OF INDIANA.

MEANS FOR LOCKING HUBS ON SPINDLES.

1,287,463.

Specification of Letters Patent.

Patented Dec. 10, 1918.

Application filed May 6, 1918. Serial No. 232,854.

To all whom it may concern:

Be it known that I, LOUIS SCHWITZER, who has declared his intentions of becoming a citizen of the United States, and a resident 5 of Indianapolis, county of Marion, and State of Indiana, have invented a certain new and useful Means for Locking Hubs on Spindles; and I do hereby declare that the following is a full, clear, and exact description there- 10 of, reference being had to the accompanying drawings, in which like numerals refer to like parts.

This invention relates to means for locking a hub on a spindle, and is adapted pri- 15 marily for use in connection with the cooling fans for internal combustion engines. The prime feature of the invention is the provi- 20 sion of a collar or ring for holding the hub of the fan on the spindle, instead of employing the usual form of nut for this purpose, which would require that the end of the spindle be reduced and threaded, thereby entailing considerable cost.

A further feature of the invention is the 25 provision of a locking ring for holding the collar in position on the end of the spindle, and a further feature of the invention is the provision of means to prevent rotation of the collar upon the spindle when desired.

30 Other objects and advantages will be hereinafter more fully set forth and claimed.

In the drawings Figure 1 is a central longitudinal sectional view through a fan hub, showing the same mounted upon a 35 spindle, parts of the spindle being broken away. Fig. 2 is a plan view of the spindle with the hub removed. Fig. 3 is a detail plan view of one end of the hub showing the locking collar thereon. Fig. 4 is an end 40 elevation thereof, and Fig. 5 is an elevation of the locking ring employed for holding the collar in position on the spindle.

Referring to the drawings in which simi- 45 lar reference numerals designate corre- 1 indicates a spindle of that class adapted to be used for supporting a fan in connection with an internal combustion engine, one end of the spindle having a threaded shank 50 2 by means of which it is attached to the

engine. Mounted upon the spindle 1 is a fan hub 3 which is preferably hollow and open at one end, the open end having a peripheral flange 4 to which is attached a spider 5 employed for supporting the fan 55 blades 6.

Heretofore it has been customary to thread the end of the spindle entering the hub 3 and place a nut thereon, but owing to the fact that the inner face of the nut 60 must be directly at right angles to the axis of the spindle to prevent uneven wear on the thrust washer, and owing to the fact that the threads become affected by con- 65 traction and expansion, difficulty has been 70 encountered in properly retaining the nut in true alinement. To overcome this objectionable feature, the end of the spindle entering the hub is left its normal diameter and a collar 7 is introduced thereover, its 75 inner face abutting against a floating washer 8, while a plate 9 preferably of fibrous sub- 80 stance, is placed against the outer face of the collar before the spider 5 is introduced into position.

The collar 7 is positively locked into po- 85 sition on the end of the spindle by means of a split locking ring 10, which snaps into a groove 11 formed in the peripheral surface of the end of the spindle, the depth of the 90 groove being such that substantially one half of the locking ring will project beyond the periphery of the spindle and abut against a shoulder 12 formed by enlarging the opening through the collar 7 at one end 95 as shown at 13, thus permitting the collar to slip over and inclose the ring to prevent the same from springing out of the groove 11.

In some instances it is desired to hold the collar 7 against rotation on the spindle 90 and to accomplish this result a slot 14 is formed in the peripheral surface of the spindle 1 and is extended longitudinally thereof the required distance, and coöperat- 95 ing with said slot is a pin 15 carried by the collar 7, said pin being attached to the collar in any suitable manner.

In attaching the fan hub to the spindle the free end of the spindle is introduced through an opening in the closed end of the 100

hub and between suitable bearing rollers 16 within the hub, the hub being introduced on to the spindle a sufficient distance to fully expose the free end of the spindle. The 5 collar 7 is then introduced over the free end of the spindle and moved inwardly beyond the groove 11, so that the locking ring 10 can be readily snapped into the groove 11, and when the pin 15 is employed for holding 10 the collar against rotation, the split portion of the ring is caused to register with the side walls of the slot 14, so as not to interfere with the movement of the collar.

After the locking ring has been entered 15 in the groove 11, the hub 3 is moved outwardly until the collar 7 is forced over the locking ring 10 thereby preventing the ring from spreading or moving out of the groove. The plate 9 is then introduced into the open 20 end of the hub, and owing to the fit of the parts within the hub, the outer face of the collar and the end of the spindle will rest against the plate 9, thus holding the hub against longitudinal movement on the 25 spindle.

By providing this form of device the hub can be very quickly attached to or removed from the spindle and the cost of production would be greatly reduced. It will also 30 be seen that a more perfect bearing will be provided as the collar will always maintain the hub in proper engagement with the spindle and will not be loosened or affected by contraction or expansion, and it will likewise be seen that when the collar is properly 35 locked upon the spindle and the hub properly assembled together, it will be impossible to release the locking means until the

spider is removed from the end of the hub, and said hub moved inwardly to permit 10 the release of the locking ring.

The invention claimed is:-

1. The combination with a spindle having a peripheral groove near its outer free end, and a hub for coöperation therewith, of a 45 collar adapted to enter the end of the hub and fit over the end of the spindle, and be moved inwardly beyond said groove, a ring adapted to snap into said groove and removably secure the collar to the spindle, and 50 means to hold the collar against rotation on the spindle.

2. The combination with a spindle, and a hub for coöperation therewith, said spindle having a circumferential groove near its 55 outer end, of a collar adapted to be introduced into the outer end of said hub and over the end of said spindle and be moved inwardly beyond said groove, and a locking ring for engagement with said groove 60 to hold the collar in engagement with the spindle.

3. The combination with a spindle having a circumferential groove and a longitudinally extending slot, and a fan hub for 65 coöperation therewith, of a collar adapted to hold the hub on said spindle, a locking ring adapted to enter said groove and hold the collar in position on the spindle, a shoulder on the collar for engagement with said locking ring, and a pin carried by the collar 70 adapted to enter said slot to hold the collar against rotation on the spindle.

In witness whereof, I have hereunto affixed my signature.

LOUIS SCHWITZER.
